UNITED STATES PATENT OFFICE.

JAMES H. BUNTING, OF NEW YORK, N. Y., ASSIGNOR TO SUSQUEHANNA SILK MILLS, OF NEW YORK, N. Y., A CORPORATION OF NEW YORK.

DESIGN FOR BROCADE.

53,358.

Specification for Design.

Patented May 27, 1919.

Application filed April 2, 1919. Serial No. 287,076. Term of patent 3½ years.

To all whom it may concern:

Be it known that I, JAMES H. BUNTING, a citizen of the United States, residing at New York, in the county of New York and State of New York, have invented a new, original, and ornamental Design for Brocades, of which the following is a specification, reference being had therein to the accompanying drawings.

The figure is a plan view of a piece of brocade showing my new design.

I claim:

The ornamental design for brocade, as shown.

In testimony whereof I hereunto affix my signature.

JAMES H. BUNTING.
